(57) **CLAIM**

The ornamental design for particulate filter for diesel engine, as shown and described.

DESCRIPTION

FIG. 1 is a front view showing a particulate filter for diesel engine according to the present invention; the rear view, the top plan view, and the bottom plan view being mirror images of the front view.

FIG. 2 is a right side view showing the particulate filter of FIG. 1.

FIG. 3 is a left side view showing the particulate filter of FIG. 1.

FIG. 4 is a perspective view showing the particulate filter of FIG. 1.

FIG. 5 is an enlarged view showing a center section of FIG. 2; and,

FIG. 6 is an enlarged view showing a center section of FIG. 3.

1 Claim, 6 Drawing Sheets
